DICKSON ADAMS, OF CANTON, OHIO.

COLLAPSIBLE CRATE OR BOX.

Application filed July 22, 1921. Serial No. 486,796.

To all whom it may concern:

Be it known that I, DICKSON ADAMS, a citizen of the United States, residing at Canton, in the county of Stark and State of Ohio, have invented a new and useful Collapsible Crate or Box, of which the following is a specification.

This invention relates to shipping crates or boxes and more particularly to a collapsible sheet metal crate designed especially for shipping fruit or vegetables although any other goods or material may be shipped therein.

The objects of the invention are to provide a crate of extremely simple construction which may be easily and quickly assembled for shipping or knocked down for reshipping.

A further object is the provision of a crate of this character in which a minimum number of designs or shapes or shapes of parts is provided, there being only two different designs necessary for the several parts comprising a single crate, the end walls and partition walls being interchangeable and the top, bottom and side walls being interchangeable, the entire structure being held together when assembled, by a single wire located around each end wall and a wire located around the partition wall in cases where the partition is used.

With these objects in view the invention consists in the construction and arrangement of parts, hereinafter described, and illustrated in the accompanying drawings, it being understood that various changes in the form and details of construction may be made within the scope of the appended claims.

A preferred embodiment thus set forth in general terms is illustrated in the accompanying drawings, in which—

Figure 1 is a perspective view of a crate embodying the invention;

Fig. 2, a transverse sectional view through the crate; and

Fig. 3, a section on the line 3—3, Fig. 2.

Similar numerals of reference indicate corresponding parts throughout the several figures of the drawings.

Although it will be understood that the crate may be made in any desired size or shape the form illustrated is an elongated crate provided with a central partition, this being the type of crate usually employed for shipping fruits or vegetables. The top, bot-

tom and side walls of the crate are interchangeable and are each designated by the numeral 1 and as shown in the drawings, each of these members is provided with the 60 spaced, transversely disposed slots 2, near each end and at the center for the attachment of the end and partition walls as will be later described.

The side and end edges of each of the 65 members 1 is turned back upon the bottom portion of the sheet as shown at 3, thus providing a reinforcing frame around the edge of each of these members and at the same time eliminating any sharp edges which 70 might cause injury to those handling the crates.

Each of the end walls and partition walls is of the same construction, these members being each indicated by the numeral 4. 75 Each of these members is provided around its edges with spaced tubular beads 5 arranged to register with the slots 2 in the side, bottom and top walls 1. The remaining portion of the edge of each of the walls 80 4 is folded back upon itself as shown at 6 reinforcing these walls and eliminating sharp edges therefrom.

In assembling the crate the tubular beads 5 of the end and partition walls are passed 85 through the adjacent slots 2 in the top, bottom and side walls, a wire 7 being passed around the outside crate and through the beads 5 of each wall 4, the ends of the wires being twisted together as shown at 8, thus 90 holding the crate in the closed position.

It will be understood of course that when the crate is assembled preparatory to filling, the top wall is placed in position, the free ends of the wires 7 extending away from the 95 crate on each side thereof. After the crate is filled, the top wall is then placed in position and the ends of the wires are passed through the tubular beads at the top of the crate and twisted together.

For the purpose of ventilating the contents of the crate, the walls 1 may be made of slightly less width than the wall 4, thus providing a longitudinal slot 9 at each corner of the crate and if further ventilation is 105 desired apertures 10 may be provided in the walls 1 and 4.

It will thus be seen that the crate embodied in the present invention is of very simple and inexpensive construction and may be easily 110 and quickly assembled as all of the longitudinally disposed walls are of one design and

2

all of the transversely disposed walls are of one design, the partitions thus being interchangeable.

In order to knock down the crate for reshipment it is only necessary to cut the wires 5 and remove the same from the tubular beads 7 after which the crate may be easily taken apart and packed for reshipment, the only new material required for reassembling 10 the crate being the wires.

I claim:

1. A collapsible crate composed of four similar side sections and two similar end sections, each end section having tubular 15 beads upon its edges, each side section having slots receiving the beads upon the end sections and wires located around the side sections and extending through the tubular beads of the end sections.
- 20 2. A collapsible crate composed of four similar side sections and similar end and partition sections, each end and partition section having tubular beads upon its edges, each side section having slots receiving the 25 beads upon the end and partition sections and wires located around the side sections and extending through the tubular beads of the end and partition sections.

3. A collapsible crate formed of four similar side sections and two similar end sections, 30 each end section having tubular extensions upon its edges, each side section having slots receiving the extensions upon the end sections and wires located transversely around the side sections and through said tubular 35 extensions.

4. A collapsible crate formed of four similar side sections and two similar end sections, 40 each end section having extensions upon its edges, each side section having slots receiving the extensions upon the end sections and wires located transversely around the side sections and engaging the extensions upon the end sections.

5. A collapsible crate composed of four 45 similar side sections and two similar end sections, each side section being of less width than the end section, each end section having tubular beads upon its edges, each side section having slots receiving the beads upon 50 the end sections and wires around the side sections and extending through the tubular beads of the end sections.

In testimony that I claim the above, I have hereunto subscribed my name.

DICKSON ADAMS.
